CIGARETTE OR CIGAR LIGHTER

Theodore H. Pattberg, Woodhaven, N. Y.

Application February 21, 1945, Serial No. 579,085

1 Claim. (Cl. 219—32)

This invention relates to cigarette and cigar lighters, and aims to provide a novel, practical useful and inexpensive portable lighter unit particularly adapted for household or home use and embodying a step-down transformer to transform the standard line voltage to a low voltage.

Another object of the invention is the provision of a novel duplex switch for closing the secondary transformer circuit through the lighter element and the primary transformer circuit independently, and of course opening the said circuits in the same manner.

A still further object is the provision of a duplex switch actuated by pushing the lighter element housing into the socket provided therefor, whereby the secondary or low-voltage circuit is closed first and the primary or high-voltage circuit is closed second, and vice versa upon withdrawal of the said housing, thereby providing a safety feature so that if anybody, particularly a child or infant, should insert a finger into the said socket no current will flow as the primary circuit remains open.

The above and other objects will become apparent in the description below, wherein characters of reference refer to like-numbered parts in the accompanying drawing. It is to be noted that the drawing is intended for the purpose of illustration only, and that it is neither intended nor desired to limit the invention in any manner to the specific details of construction shown excepting insofar as they may be deemed essential to the invention.

Referring briefly to the drawing, Fig. 1 is a perspective view of a representative type of a separable lighter unit per se.

Fig. 2 is a central cross-sectional elevational view through the housing containing the transformer and switch actuatable by insertion of the lighter unit of Fig. 1 into the socket provided in the said housing.

Fig. 3 is a fragmentary perspective view of Fig. 2, clarifying the structure and functioning of the switch actuating mechanism.

Fig. 4 is a wiring diagram.

Referring in detail to the drawing, the numeral 10 indicates the base of the device and 11 the housing or shell mounted thereon and provided with a socket opening 12. The device may be portable and adapted to be set upon any plane surface of an article of furniture, such as a table, or, if desired, the base 10 may be secured against a wall to fix the device in position. A step-down transformer 13 having a 120-volt primary and a 6-volt secondary, or the

like, is mounted on the base 10, the primary leads thereto being indicated at 14 and 15 and the secondary leads at 16 and 17. A connecting lead 18 passes through the housing 11 and has a plug 19 thereon for connecting the device to a wall outlet, not shown.

Bracket arms 20 and 21 support a cup-like member 22 with its open end in the housing opening 12. An opening is provided through the center of the bottom 23 of the member 22, and insulating washers 24 are mounted on each side of the bottom 23 with a screw 25 passing therethrough and having its head inside the cup 22 with a walled washer or the like 26 clamped between the said screw head and the upper insulating washer 24.

A coiled spring 27 of rather heavy construction stands upright and has its base secured in the washer 26. A pan 28 is mounted upon the upper end of the spring 27 in horizontal position and is provided with a central boss or button 29.

The lighter unit 30 has a heating element 31 wound in the form of a plane spiral in accordance with standard construction, one end of said spiral being connected to a central button or boss 32 and the other or outer end being connected to the peripheral ring 33 in electrical contact with the band 34. An insulating washer or disc 35 is mounted inward of the spiral element 31.

A lever 36 is pivotally mounted at 37 on the bracket arm 21 and is formed of two members or layers 38 which are spread apart for a distance intermediate the length of the lever to pass the sides of the cup 22. Opposed openings 39 are formed in the cup 22 through which the ends of opposed tongues 40 formed on the members 38 of the lever 36 project into the cup. It is now apparent that upon insertion of the member 30 into the cup, its button 32 will contact with the button 29 but at the same instant, or just before or after the said contact is made, the band 34 of the member 30 will contact the lever tongues 40 and be stopped thereby unless greater force is applied on the member 30 as will be hereinafter set forth.

A bracket 41 slidably supports a pin 42 in vertical position, and the upper end of this pin is engaged in the end 43 of the lever 36. A coiled spring 44 surrounds the pin between the lever end 43 and the bracket 41 and has its upper end 45 anchored to the pin, thus normally urging the said pin upward. A contact head 46 is provided on the lower end of the pin, and therebeneath

are a pair of spaced spring contacts 47 supported on the bracket 41 by an arm or the like 48 of insulating material.

If desired, a signal lamp socket 49 may be provided, mounted on a bracket 50, to signal through an opening 51 in the shell 11 that the device is functioning, as will later be described.

The primary lead 15 of the transformer is connected to one contact 47, and the other primary lead 14 goes through the plug lead 16. The other plug lead wire 52 is connected to the other contact 47. The secondary lead 18 is connected to the screw 25 by a nut 53, and the other secondary lead 17 is grounded to the frame at 54. The shell of the lamp socket 49 is grounded on its bracket 50, and its button 55 is in contact with an arm 56 secured to the bracket 50 by insulating member 57. A lead 58 joins the arm 56 to the secondary lead 18. Thus the lamp 59 is in parallel with the pan button 29 and ground.

Upon insertion of the member 30 into the cup socket, as above-mentioned, contact is closed between the buttons 29 and 32 and hence the circuit through the lamp 59 is also closed. No current flows, however, as the primary circuit remains open. Further insertion of the member 30, with greater force, moves the pan 28 downward against its spring 27 and simultaneously, because of contact of the band 34 against the lever tongues 40, tilts the left-hand end of the lever downward against the spring 44. When the lever has been tilted sufficiently the head 48 will bridge the contacts 47 to close the primary circuit,

whence secondary current will flow through both the lighter element 31 and the lamp 59. As is usual, the lighter unit is held in the latter position for a sufficient length of time for its element 31 to become red hot. Upon removal thereof, the primary circuit is opened first and then the secondary circuit.

Obviously modifications in form and structure may be made without departing from the spirit or scope of the invention.

I claim:

In combination with a member having a heating element therein, a device including a housing having a socket-like cup and having a transformer mounted therein, means for closing the circuit through the secondary of said transformer and said heating element upon insertion of said member into said cup a certain distance, means for closing the circuit through the primary of said transformer upon further insertion of said member an additional certain distance in said cup, said means for closing said primary circuit comprising a lever pivotally mounted at one end in said device and extending past said cup, said cup having an opening therethrough, said lever having a tongue projecting through said opening into said cup, the free end of said lever having circuit-closing means connected in series with said primary circuit, said tongue lying in the path of said member upon insertion of said member into said cup.

THEODORE H. PATTERSON.
